UNITED STATES PATENT OFFICE.

HARRY E. REED, OF SMITH CENTER, KANSAS.

WAGON END-GATE.

1,303,390.

Specification of Letters Patent. Patented May 13, 1919.

Application filed September 3, 1918. Serial No. 252,383.

To all whom it may concern:

Be it known that I, HARRY E. REED, a citizen of the United States, residing at Smith Center, in the county of Smith, State 5 of Kansas, have invented certain new and useful Improvements in Wagon End-Gates; and I do hereby declare the following to be a full, clear, and exact description of the invention, such as will enable others skilled 10 in the art to which it appertains to make and use the same.

This invention is an improvement in closures and has particular reference to an end gate for wagons.

15 An object of the invention is to provide an improved end gate particularly adapted for use on wagons carrying grain, potatoes or other like articles in bulk and constructed so that the same may be adjusted 20 to a position to permit of the unloading of the wagon without the necessity of completely detaching the gate.

Another object is to provide an end gate of this character which is simple in construction easy to manufacture and effective 25 in carrying out the purpose for which it is designed.

The inventive idea involved is capable of receiving a variety of mechanical expressions one of which for the purpose of illustrating the invention, is shown in the accompanying drawing wherein:—

Figure 1 is a front elevation of the end gate constructed in accordance with the invention.

Fig. 2 is a horizontal section on the line 2—2 with the gate in closed position.

Fig. 3 is a similar view with the gate in opened position.

40 Fig. 4 is a section on the line 4—4 of Fig. 1.

Fig. 5 is a section on the line 5—5 of Fig. 1.

Referring more particularly to the accompanying drawing the numeral 10 indicates the body of a wagon the sides of which are provided at the rear end thereof with the vertical cleats 11 between which the ends of the gate are disposed when the 50 same is in its closed position.

The end gate preferably comprises a pair of sections 12 and 13 formed of rectangular pieces of wood having their inner ends spaced and outer ends adapted for engagement between the cleats 11 when the gate is in closing position. The inner end of the section

12 has secured thereto one end of a rectangular plate 14 made of iron or any other suitable material and said end of the plate is countersunk within a recess 15 formed in 60 the adjacent end of the section 12 so that the outer faces of said plate and section will be flush. The section 13 likewise has secured to its inner end, by rivets or other fasteners 16, one end of a plate 17 similar 65 in construction to the plate 14 and the free ends of said plates are arranged in overlapping relation both when the gate is in its closed and opened positions. Cleats 18 and 19 are secured to the section 12 transversely thereof and similar cleats 20 and 20' 70 are fastened to the section 13 in a similar manner.

In order to support the end gate in its opened position and permit of a pivotal 75 movement thereof with respect to the end of the wagon body whereby the gate may be raised in order to allow the contents of the wagon to be unloaded, there is preferably provided a pair of inverted U-shaped hangers 80 21 the ends of which are secured to the sections 12 and 13 on either side of the upper end of the cleats 18 and 20 and the bight portions of said hangers extend above the upper edge of said sections and are engaged in supporting straps 22 secured to an upper end gate section or cross brace of the wagon body whereby to permit of an outward swinging movement of the lower end 85 of the end gate about said bight portions as 90 pivots when the sections 12 and 13 have been adjusted toward each other to their opened positions, the straps 22 being made of a width considerably less than that of the hanger 21 so as to allow a sliding movement 95 of the bight portions of the hangers in the straps when the gate is adjusted to opened and closed positions.

Upper and lower horizontal braces 23 and 24 are provided for the sections of the end gate and are preferably formed of channel iron bars and are secured to the cleats 18 and 20 respectively. The bars are of a length sufficient to abut against the cleats 11 when the lever is operated. By this arrangement it will be seen that when the bars bear against the cleats 11 they act as stops to assist the lever in moving the section 12 out of the cleats 11. One end of the bar 23 is secured to the upper end of the 105 cleat 18 on the sections 12 while the other end extends under the roller 26 carried by 110

the bracket 27 which is secured to the cleat 20. The roller 26 is engageable with the bottom of the U-bar and adapted to guide the movement of the section 13 to opened and closed positions. Similarly the bar 24 has one end secured to the lower end of the cleat 20 while its opposite end passes under a roller secured to the cleat 18 in the same manner as the roller secured to the cleat 20.

10 To further guide the sections 12 and 13 in adjustments the plate 14 has extending from its outer surface a plurality of studs 29 arranged in vertically staggered relations and projecting through a horizontal slot 30 formed in the plate 17 and movable from one end to another in said slots when the sections of the gate are adjusted.

The means for adjusting the sections toward and away from each other to open and close the gate preferably comprises a lever 31 having one end pivotally mounted upon a vertical axis and disposed between the pivot ears 32 extending from the plate 14. At a point adjacent the pivoted end of the lever the same also has pivoted thereto adjacent ends of the links 33 the other ends of which are pivoted to the plate 17, at 34. When the sections 13 of the gate are in their closed or extended positions the lever 31 is arranged in substantially parallel relation to the sections and has its free end locked to prevent outward swinging movement of the lever about its pivot. For the purpose of locking the free end of the lever the same is provided with an opening through which projects a vertically adjustable locking pin 35 slidable through a bracket 36 secured to the cleat 20 and having coiled thereabout a spring 37 which normally forces the locking pin downwardly to its operative position. The pin is provided at its upper end with a laterally extending handle 38 adapted to be grasped in order to adjust the pin vertically to disengage the lower end thereof from the opening in the lever 31 after which the free end thereof may be swung outwardly. This outward swinging movement of the lever will, by reason of the links 33, draw the sections 12 and 13 inwardly toward each other and adjust the same to their opened positions after which the lower end of the gate may be swung outwardly and upwardly to permit of a discharge of the contents of the wagon.

55 What is claimed is:—

1. An end gate comprising a pair of relatively adjustable sections, plates secured to the inner ends of said sections and having free ends arranged in overlapping relation, a cleat carried by one of said sections, a le-

ver having one end pivotally connected to one of said plates, links pivoted to said lever and also to the other plate whereby swinging movement of said lever will adjust the sections toward and away from each other, and a lock device carried by said cleat and engageable with the free end of said lever whereby to retain said sections in their closed positions.

2. An end gate comprising a pair of relatively adjustable sections, plates secured to the inner ends of said sections and having free ends arranged in overlapping relation, a cleat carried by one of said sections, a lever having one end pivotally connected to one of said plates, links pivoted to said lever and also to the other plate whereby swinging movement of said lever will adjust the sections toward and away from each other, a lock device carried by said cleat and engageable with the free end of said lever whereby to retain said sections in their closed positions, straps for supporting said sections and hangers secured to said sections and engageable in said straps to pivotally connect the sections thereto, said hangers being slidable in said straps when the sections are adjusted toward and away from each other.

3. An end gate comprising a pair of relatively adjustable sections, plates secured to the inner ends of said sections and having free ends arranged in overlapping relation, cleats carried by said sections, a lever having one end pivotally connected to one of said plates, links pivoted to said lever and also to the other plate whereby swinging movement of said lever will adjust the sections toward and away from each other, a lock device carried by one of said cleats and engageable with the free end of said lever whereby to retain said sections in their closed positions, one of said plates having longitudinal slots therein, studs carried by the other plate and engageable in said slots, horizontal brace bars for said sections having opposite ends thereof secured to the cleats carried by said sections, rollers carried by certain of said cleats and engageable with the other ends of said brace bars, and means for pivotally and slidably supporting said sections to permit of an outward swinging movement thereof and adjustment toward and away from each other.

In testimony whereof, I affix my signature, in the presence of two witnesses.

HARRY E. REED.
